HEINRICH ZIMMERMANN, OF KITZINGEN-ON-THE-MAIN, GERMANY.

HORSEHAIR SPINNING AND CURLING MACHINE.

Application filed August 8, 1927, Serial No. 211,543, and in Germany August 14, 1928.

Horsehair is treated for upholstery purposes by spinning the same to a cylindrical thread, 8 to 15 mm. thick, this thread being twisted to form a strand in which the thread-windings are close together in helical line. This curled thread is steamed and dried and untwisted and unraveled. Horsehair is not often used alone owing to its high price but generally admixed with cheap elastic hair as 10 hog's bristles or together with even cheaper vegetable-fibres as fibre, or cocoa-nut fibre. These admixtures reduce considerably the price of the upholstery-material but they give to the material, which is never quite homogeneously mixable, at different points quite different properties. Owing to this disparity of properties at different points, the material could up to the present never be spun to a thread and twisted to a curl in a 20 purely mechanical manner. A commonly used machine, in which the pulling of the material into the spinning head, the pulling of the spun thread through the guide-roller of the spinning head and the twisting and 25 winding-up of the curl have to be effected exclusively by the driving mechanism of the winding-up drum makes it necessary, that the material has to be fed to the machine by a skilled rope-maker to whom high wages 30 have to be paid and who must retain the material in excess and smooth with the list the pulled in material during the twisting. The spinning head of the machine plays only the part of the rotating rope-hook onto which, at 35 the spinning on the rope-walk, the eye of the bundle of material is hooked. The rope-maker may remain sitting in front of the hollow shaft of the spinning head during the guiding and smoothing with the list instead 40 of walking backwards from the rotating hook as on the rope-walk, but this advantage does not reduce the wages, as the rope-maker has to be paid.

By this invention a machine has been 45 created which spins and curls in continuous operations any kind of horsehair mixtures without subsequent supplying of the same by hand, and which produces at high efficiency a perfect curl. This result is substantially 50 due to three new mechanisms. The first mechanism serves to adjust the horse-hair and fibres parallel to one another prior to the twisting, to stretch the same and to push the same together from an originally wide hair-band to a small one. The second mechanism 55

serves for pulling the spun thread, independently of the pull exerted by the curl, automatically through the spinning head and to maintain it stretched. The third mechanism serves to twist the curl, to wind the 60 same up and to maintain the same just sufficiently stretched.

A machine fitted with these three mechanisms is shown, by way of example, in the 65 accompanying drawings.

Fig. 1 shows the whole machine in longitudinal section.

Fig. 2 shows on larger scale in longitudinal section a portion of the mechanism for stretching and adjusting the hair, and the 70 spinning head with the automatic thread pulling device.

Fig. 3 shows the stretching and adjusting mechanism in top plan view and the spinning head mechanism in a longitudinal sec- 75 tion at right angles to that shown in Fig. 2.

Fig. 4 is a cross section on line 4—4 of Fig. 3 viewed from the right end.

Fig. 5 shows in longitudinal section the mechanism for twisting and winding up the 80 curled thread.

Referring to the drawings *a* is the endless conveyer-band, *b* the pin-drum, *c* the pin-cover and *d* the endless delivering-band of a 85 hackling machine of known type. The de- 90 livering band *d* is continued by a frame, not shown, in which for instance five pairs of cylinders 1 to 5 are mounted in a row, the cylinder-pairs being driven by chain-drives, not shown, each following pair at higher 95 speed than the preceding pair. The two cylinders of each pair are driven by pairs of spur-wheels not shown in the drawing, so that they rotate in opposite directions, in the directions of the arrow-lines *f* in Fig. 2, the 100 cylinders of each following pair having the tendency to pull the strand *g* of bundles of hair from the preceding pair of cylinders and to feed the same to the next following pair of cylinders. As shown in Fig. 2, at the pair 105 of cylinders 3, these cylinders are fluted in axial and circumferential directions, so that the teeth *h* thus formed, grip strongly into the strand *g*, although this strand can pass between the teeth. In the intervals between 110 the pairs of cylinders the strand *g* is guided on table-plates *i*, the side-walls *k* of which converge funnel-shaped in forward-direction, the converging becoming narrower from table to table. By the co-operation of all 115

the pairs of cylinders and of the converging guide-walls *k* of the table-plates the bundles of hair, which come from the hackling machine still undulated and entangled, are adjusted in many stages, parallel to one another, stretched in straight lines and pushed together to form a narrow strand. When the strand of hair passes between the cylinders of the first pair it is for instance 40 cms. wide, while it is only 4 cms. wide when arriving between the cylinders 5 of the last pair. This adjusting, stretching and pushing together of the hair, prior to the spinning, is extremely important for obtaining a thread as uniformly thick and smooth as possible and having as few ends of hair and fibre as possible sticking out from the thread.

The hair-strand coming from the last pair of cylinders 5 is then pulled into a stationary 20 clamping and smoothing block *m* which serves as a substitute for the list and for the hand of the rope-maker which feeds the same on as in rope-making by hand. On the top-face of the clamping block tilting wedges *p* 25 with counter-weights *o* are hingedly mounted at *n*, said wedges forming, together with the bottom *q* of a vertical clamping-block-groove *r*, an introducing funnel *s, s'* continued by a rounding channel for the narrow hair-strand. 30 Onto the string of hair pulled together in the rounding channel the wedges *p* are pressed in such a manner that the strand can be spun back only to the point which is most strongly clamped, the strand being smoothed at the 35 pulling through.

The pulling forward of the strand of hair under the clamping wedges *p* and the simultaneous spinning of the same to a thread are effected by means of a spinning head *x* 40 mounted in known manner on a hollow driving shaft *w* which is adapted to be rotated at different speeds by driving wheels *u, v*, of different diameters. Thread-rollers 6, 7, 8 having wedge-shaped grooves, are mounted 45 between the arms *y* of said spinning head. The thread *t*, when coming from the shaft *w*, comes into contact with the first thread-roller and moves in serpentine-windings over the second and third rollers, the third thread- 50 roller being driven, for instance, from a stationary toothed crown *g* by means of a planet-wheel 10 and of a bevel-wheel-drive 11, 12. The manner in which this third thread-guide is driven is secondary, the main condition is 55 that this roller has a wedge-groove which clamps the thread and pulls the same, the thinner portions of the thread being clamped in the wedge-shaped groove quite as securely as the thicker portions, the thread being neither flattened nor roughened.

Between the arms *y* of the spinning head *x* a guide-cross for the thread is mounted in front of the pulling roller 8, said cross consisting of a pulling cylinder 16, driven from 60 the shaft 13 of the pulling roller through

the intermediary of spur-wheel gears 14, 15, the thread being wound completely around said cylinder 16 in order to prevent propagating of the curling in rearward direction, and of a transverse-tube 17 loosely rotatable and 70 arranged directly behind the cylinder 16. This transverse-tube serves to separate the thread-side which is running up on the pulling cylinder from the thread-side coming from this cylinder so that these thread-sides 75 cannot get entangled. The cylinder 16 participates in the drawing forward of the thread, its main object being, however, to prevent the curl *T* from jumping back behind it and further the transmission of the pull of the 80 curl of the thread, as thereby the regular spinning of the thread would be impeded.

The pull exerted upon the thread must never become so strong as that on the curl. In order to twist the thread under the required pull to form a curl the following mechanism is provided. The hollow shaft 18 (Fig. 5) can be rotated by two kinds of driving wheels 19, 20 at different speeds, but in any case more rapidly than the spinning head-shaft *w*. A curling crank 21 rotates with the shaft 18 and turns the curl which is guided by means of guide-pulleys 22, 23, 24 around a winding drum, arranged in alignment with the machine-axis. The rotation 90 of this drum is braked, for instance, by a band-brake 25, 26. The brake-disk 25, upon which the band 26 acts, is keyed on a shaft 27 on which a winding-up drum 29 is shiftably mounted by means of key and groove 28. The resistance, which the drum 29 opposes to the curl, can be regulated by adjusting the brake 25, 26. When the brake-drum retards with regard to the curl-crank, the curl is wound up on the drum. The pull to be 95 exerted on the curl, and which is adapted to be adjusted by the brake, depends on the thickness of the curl actually produced and on the composition of the material of harder and softer hair and fibres. In any case it is 100 easy to obtain a curl which is twisted neither too little or too much, i. e. is neither too soft or too hard and which, after having been steamed and dried, can be easily untwisted and unraveled.

It is obvious that for the feeding of the working material it has merely to be laid upon and spread onto the endless conveying band *a*. This work can be done by an ordinary work-woman, no rope-makers being required for guiding and smoothing the material. The improved machine supplies a curl which is more uniform and smoother than those made by hand with the aid of a curling tube, i. e. a curl in which all hair or fibres of whatever length, thickness, hardness and elasticity are perfectly twisted in. The curl produced on the improved machine is further easier to untwist and to unravel than the curls made on the commonly used 115 120 125 130

machines as the hair and fibres of the same are not felted the one into the other. The advantage of the easier untwisting and unravelling is greatly appreciated by the upholsterers 5 who have to carry out this work. An upholstery material consisting of hair and fibres, undulated only along helical lines, is obtained.

The improved machine presents for the 10 manufacturers of the curl, besides the saving of a rope-maker, the advantage that there occur almost never interruptions of service, so that one engineer can attend to a whole row of machines, the only work he has to do 15 being to interchange full winding drums against empty ones.

I claim:—

1. A horsehair spinning and curling machine mounted in alinement with a hackling 20 machine of known type, comprising in combination a row of cylinder-pairs arranged close behind each other, each following pair driven at a higher speed than the preceding pair, said cylinders being fluted in axial and 25 circumferential directions, stationary plane guide-table-plates adapted to straddle the intervals between the several pairs of cylinders with their lower edges bearing against the lower cylinders, side-walls on said table- 30 plates converging almost continuously in the direction of movement of the strand and having rounded edges near the upper cylinder, and a clamping block following directly on the extreme pair of cylinders and the 35 corners of the ends rounded at the upper and lower edges facing the last pair of cylinders being close to the upper and lower cylinders and to which a small hair band is supplied 40 which is composed of hair and fibres adjusted parallel to one another and stretched gradually in several stages.

2. In a horsehair spinning and curling machine as specified in claim 1 the clamping block having a vertical clamping groove extending over its entire length, tiltalbe wedges 45 in said clamping groove and hingedly mounted on the top-face of said clamping block said grooves and clamping blocks forming together an introducing funnel and a 50 rounding channel for the horsehair and fibres, and counter-weights on said tiltalbe wedges so that said wedges press onto the strand of hair to prevent unspinning of the same 55 beyond the point which is submitted to the strongest clamping action and for smoothing

said strand when the same is being pulled through.

3. A horsehair spinning and curling machine as specified in claim 1, comprising in combination with the clamping block and 60 clamping wedges, a hollow driving shaft, driving wheels of different diameters on said shaft for rotating the same at different speeds, a spinning head keyed on said driving shaft and having arms, thread-guide-rollers 65 between said arms of said spinning head and having each a wedge-shaped circumferential groove the first guide-roller receiving the thread coming from said hollow shaft the second and third guide rollers guiding the 70 thread in serpentine lines, and a driving mechanism for driving said third guide-roller and consisting of a stationary toothed crown, a planet-wheel rolling on said toothed crown and a pair of bevel-wheels the one rotated 75 from said planet-wheel and the other rotating the axle of said third guide-roller.

4. In a horsehair spinning and guiding machine as specified in claim 1, in combination with a spinning head and three guide- 80 rollers in the same, a guide-cross for the thread mounted in said spinning head in front of said third guide-roller and consisting of a pulling cylinder, a spur-wheel-gear for rotating said pulling cylinder from the axle of 85 said third thread-guide roller, and a loosely rotatable transverse-tube behind said pulling-cylinder and designed to keep the thread-side which is running up on said pulling cylinder spaced from the thread side which is running 90 off said pulling cylinder to prevent entangling of the two-thread sides.

5. In a horsehair spinning and curling machine as specified in claim 1, in combination with a pulling cylinder and with a spinning 95 head, a curling crank, a hollow driving shaft on which said curling crank is mounted, means for rotating said hollow shaft more rapidly than said spinning head, guide-pulleys for the curl-string, a shaft in alinement with the axis of the machine, a band-brake on said shaft, and a winding up drum 100 shiftably mounted by key and groove on said shaft and around which the curl strand is wound by said curl-crank the speed at 105 which said curled strand is pulled forward being regulated by said band-brake.

In testimony whereof I affix my signature.

HEINRICH ZIMMERMANN.
